RAZOR BLADE HOLDER

Filed Nov. 2, 1926

Inventor

A. M. NICHOL,

By

Paul L. Smith

Attorney

UNITED STATES PATENT OFFICE.

ARTHUR MONTGOMERY NICHOL, OF CLEVELAND, OHIO.

RAZOR-BLADE HOLDER.

Application filed November 2, 1926. Serial No. 145,877.

This invention relates to devices for holding razor blades while honing, stropping or otherwise sharpening the same, and has for an object to provide a holder adapted for use with cutting blades of the "Gillette" type, wherein means are arranged for guarding one of the edges while the other is exposed for sharpening, the guard being so disposed as to enable its being readily shifted 10 and clamped, from one position to the other without risk of unclamping, while in use.

A further object of my invention resides in a holder of this character which is extremely simple, compact and due to the fact 15 that it readily lends itself to manufacture on a high production basis, may be placed on the market at a very low cost. The scope of my invention extends to whatever construction may be defined by or included with- 20 in the terms or language of the appended claim.

In the drawings:

Figure 1 is a plan view of my improved razor blade holding device;

25 Figure 2 is an edge view thereof;

Figure 3 is a transverse sectional view on the line 3—3 of Figure 1, looking in the direction of the arrows,

30 Figure 4 is a view in perspective illustrating my device in an open position as when receiving a blade, and

Figure 5 is a plan view of another embodiment of my invention.

My invention, in the form or embodiment shown in the drawings and briefly described, comprises a pair of clamping members, 10 and 11, which are provided at one of their ends with hinged portions, 12, through which the pin, 13, extends for pivotally 35 mounting them. For the purpose of strengthening the clamping members, 10 and 11, and for facilitating their being readily handled, I provide each with a longitudinally extending outwardly bulged portion 40 along their substantial entire length.

The handle, 11, is formed with a plurality of upwardly extending struck-up portions, or lugs, 14, located adjacent to the hinged end, which are of a diameter and of the 45 required distance apart to accommodate the ordinary double edged blade of the Gillette type. It is obvious, of course, that these lugs may be formed to accommodate blades of other types.

50 55 It will be noted with reference to the several figures of the accompanying drawings

that the razor blade, 15, is securely held flatwise between the clamping members, 10 and 11, when the blade is in its locked position, or as shown in Figure 3. The lugs, 14, pass 60 through the respective openings in the blade, and their upper extremity substantially fit the inner side of the outwardly bulged portion of the clamping member, 10, for preventing any sidewise movement between the 65 clamping members.

For the purpose of providing an efficient guard for the unexposed edge of the safety razor blade, 15, and a means for securely clamping or locking the handles, 10 and 11, 70 I provide a swiveled arm, 16, which preferably extends slightly beyond the extreme ends of the clamping members. The guard, 16, is substantially U-shaped in cross section along its entire length for not only strengthening and preventing its distortion, but for the purpose of permitting each of its edges, 16', to bear against the outwardly bulged portions of the clamping members, 10 and 11, for firmly holding them together. 80

A connecting strip, 17, extends between the hinged portions of the member, 11, preferably formed integral therewith, and is slightly spaced from them, as is shown in Figure 1 for the purpose of receiving the 85 headed end of the pivot, 18, of the swivel block, 19. The guard, 16, is, in turn, pivoted to the swivel block, 19, as indicated at 20, which it will be noted is arranged transversely or at a right angle with respect to 90 the pivot, 18.

By reason of the fact that the pivots, 18 and 20, are centrally located with respect to the clamping members, 10 and 11, the guard may be effectually swung from one 95 edge of the handle to the opposite edge, as, for example, when it is desired to hone or strop both edges of the same blade. This is illustrated by dotted lines in Figure 1, wherein the guard, 16, is shown as removed 100 from the upper edges of the clamping members, 10 and 11, and is about to be clamped against the lower edges of the clamping members.

In the embodiment of my invention illustrated in Figure 5 it will be noted that the hinge, 12, and the swivel member, 19, are located on the ends of the clamping members, 10 and 11, opposite from the end on which the blade, 15 is held. In this form 110 of my invention the pivotal points being located on the hand holding end, the oppo-

site or blade holding end may be relatively shortened.

I am aware of the fact that there are a great many devices for resharpening safety razor blades, but I know of no device which is as simple, absolutely safe from a practical standpoint and as highly effective as my present safety razor blade holder and stropper.

I claim:

10 In a razor blade holder, comparatively flat blade like clamping arms, means for fixing a razor blade between and relative to said arms, said blade projecting beyond the arms in both directions, and a single blade-

guard of U-shape in cross section swiveled 15 at one end of the arms to permit the guard to be moved to either side of the arms, said guard when in operative relation to the blade completely enclosing the projecting portion 20 of the blade at one side of the arms and clamping the adjacent edges of the arms, the guard beyond the blade-enclosing portion clamping the similar edges of the arms and serving with said arms to provide a handle portion, whereby the guard is prevented 25 from inoperative movement while the holder is in use.

ARTHUR MONTGOMERY NICHOL.
